FREDERIC J. HOFSCHEIDER, OF ROCHESTER, NEW YORK.

HYPODERMIC SYRINGE.

Application filed November 5, 1925. Serial No. 67,144.

My invention relates to a hypodermic syringe, and has for its principal object to afford a durable, efficient, and economical all metal construction, such that it can be thoroughly sterilized, and is adapted for dentists' use.

A more particular purpose of the improvement is to afford an arrangement that permits a needle carrier to be held in operative relationship to the barrel of a syringe solely by frictional engagement, thus eliminating the necessity of attaching means for the needle carrier.

An additional object of the invention is to construct and hold the needle carrier in such manner as to afford a thoroughly water-tight connection while making it possible to position or remove the needle carrier instantly and without difficulty.

Still another purpose of the improvement is to attach a needle within a needle carrier in such manner as to permit sufficient flexibility of the needle to prevent ready breakage, thus increasing the life of the needle by causing it to withstand any ordinary strains to which it may be subjected.

A further object of the invention is to afford a watertight connection between the piston and barrel of a syringe without employment of washers of leather, soft metal, or the like, and to accomplish this result with a part or parts formed of hard metal and constructed so as to be elastic.

An additional purpose of the invention is to afford an arrangement that permits of quickly and effectively gripping the piston, to produce a water-tight connection between it and the barrel of the syringe, by means of an elastic, hard metal unit.

A further object of the invention is to bring about the stated results with a simple construction and arrangement of parts that can be manufactured at a low cost, giving to the user a structure that will stand up successfully under hard, long usage and which can be thoroughly sterilized without taking apart.

With these and other ends in view, the invention includes the form and arrangement of parts that will appear clearly from the following description when read in conjunction with the accompanying drawings, the novel features being pointed out in the claims following the description.

In the drawings:

Figure 1 is a side elevation of a hypodermic

syringe made in accordance with one embodiment of my invention;

Figure 2 is an enlarged longitudinal sectional view of the same, with parts in elevation;

Figure 3 is a sectional view of the needle carrier;

Figure 4 is a similar view showing a slightly modified form of needle carrier;

Figure 5 is an elevation of the inner end of the needle carrier;

Figure 6 is a detail sectional view of the sleeve used to tighten the gripping member about the piston, and

Figure 7 is a detail side elevation of the needle carrier, showing a portion of the syringe barrel in section, and illustrating the piston handle in position when used to remove the needle carrier from the barrel.

The various features of my invention may be carried out in many different ways, and the several arrangements herein shown are intended merely as exemplary of various possible practical embodiments.

In the arrangement shown, 1 designates the barrel of a syringe, 2 is the piston, and 3 is the piston handle, which will be referred to more fully hereinafter.

The barrel 1 is provided with a tapered opening at its outer end to receive a needle carrier 4 which has an exterior surface tapered correspondingly with the opening in the barrel, and adapted to be held in the barrel solely by frictional engagement. The inner end of the needle carrier has a reversely tapered portion 5 provided with sediment deflecting means, preferably in the form of a spiral groove 6 which acts, as the piston is forced inwardly, to cause any heavy particles in the fluid to be swirled to the side wall of the barrel and retained in the pocket 7.

8 designates a needle, rigidly secured to the carrier at the rear end of the latter, as designated at 9, either by soldering, compression of the carrier, or in any other suitable manner. Except where the needle is attached at the rear end of the carrier, it is free from the adjacent walls of the carrier. The latter is preferably provided with an enlarged opening at its central portion having concave walls 10, and a reduced portion formed by convex walls 11 near its forward end in close proximity to the needle, the forward end of the opening being flared as at 12.

This arrangement permits the needle to be flexed throughout its length as it meets with

resistance and prevents it from breaking as is likely if rigidly held at the front end of the carrier without provision for play or flexing. The structure of Figure 3 shows the 5 convex walls 11 spaced slightly from the needle, this form being desirable where a stiff or heavy needle is employed, but when a fine gauge needle is used, the arrangement of Figure 4 is preferable. In this arrangement, the inwardly projecting portions 13 of the carrier are in contact with the needle, although not connected thereto, and serve to brace the needle at this point, while at the same time permitting endwise movement and 10 flexing of the needle. The needle carrier may be provided with a series of annular grooves 14 in its tapered surface which act to create a tighter and more perfect union with the surrounding tapered surface of the barrel, 15 since the sharp edges afforded by the grooves have a tendency to finish the surface of the barrel or remove any slight irregularities each time the needle carrier is forced into 20 position.

25 To assemble the needle carrier in the barrel, the piston 2 must first be removed. The needle carrier is then dropped in the upper end of the barrel and permitted to fall into the lower end. Then by inserting the piston 30 and slightly tapping the inner end of the needle carrier, the latter is properly positioned and is held frictionally until removed by a blow or sufficient pressure upon the outer end of the needle carrier. When desired to 35 remove the needle carrier for sterilizing the parts, if the needle is worn out or broken, a blow upon the outer end of the needle carrier will loosen and permit it to drop out of the barrel, after the piston has been first removed. If it is desired to preserve the needle and remove the needle and carrier from the barrel, the portion 15 of the handle 3 is employed. The piston being removed from the barrel, the opening 16 of portion 15 is positioned over the needle and against the outer 40 end of the carrier as shown in Figure 7, and a sufficient pressure on the needle carrier can be then exerted to loosen it from the barrel, without damaging the needle. I will now 45 describe the parts which serve to form a water-tight connection between the piston and barrel.

50 The practice heretofore has been to employ washers of soft metal, leather, asbestos, or other compressible material to effect a liquid-tight joint between the barrel and piston. This has the disadvantages that with leather or asbestos, sterilization is not practically 55 feasible, and where soft metal is employed, it is quickly rendered useless by distortion, and frequent movement of the piston causes particles of the metal to chip off and get into the hypodermic solution. To overcome these 60 objections, I have devised a joint that utilizes 65 only hard metal, which is elastic but not

readily subject to permanent distortion. Thus I obtain a thoroughly liquid-tight connection or joint between the piston and barrel, such that all portions of the instrument can be quickly and completely sterilized, and 70 there is no possibility of foreign matter getting into the solution.

To accomplish this, I employ piston-gripping means which is preferably a cylinder formed integral with the barrel 1, as shown in 75 Figure 2. The piston-gripping cylinder is of hard metal, but elastic, so that it will under pressure grip the piston and will return to normal position and release the piston when pressure is removed. The outer surface of the 80 piston-gripping cylinder is tapered as shown, and provided with a series of parallel annular grooves 22 affording intermediate rings 23, and permitting sufficient elasticity in the cylindrical portion 21 so that it may be compressed about the piston 2 without being permanently distorted. This action of the piston-gripping cylinder may be brought about 85 by a sleeve 24 having an inner tapered surface 25 that engages the correspondingly tapered surface of the piston-gripping cylinder portion. The sleeve 24 is threaded interiorly at its lower end to engage a threaded portion 26 on the barrel and by turning the 90 sleeve 24 so as to thread it on the barrel, its tapered surface forcing against the tapered surface on the piston gripping cylinder, compresses the latter around the piston 2. With 95 very little effort, a sufficiently tight engagement between these parts can be obtained to prevent any loss of liquid between the piston and barrel.

In order to turn the sleeve 24, it is provided with a keyway 27 that is engaged by a 100 corresponding key 28 on the handle portion 3 of the piston, see Figure 2. In this way, the sleeve 24 is tightened by a slight turning movement of the handle 3 and piston with the latter in position in the barrel, and may be loosened in the same manner. 29 is a hammer 105 portion on the handle that is used to knock the needle carrier from the barrel when the needle is broken or worn out. Under these conditions, the needle carrier is removed by 110 tapping its outer end with the hammer portion 29.

In using the syringe, assuming it to be 115 disassembled, a needle carrier is dropped into the upper end of the barrel 1 with the needle 120 pointing downwardly, so that when it falls to the lower end of the barrel it assumes the position shown in Figure 2. The piston 2 is then inserted and pushed downwardly into the barrel to impose pressure on the inner end 125 of the needle carrier. This forces the needle carrier into sufficiently tight frictional engagement with the barrel to retain it in place. The piston being in position, the key 28 is then brought into engagement with the keyway 27 and piston handle 3 turned until suf- 130

ficiently tight engagement is had between the piston and piston-gripping cylinder to permit free movement of the piston and yet prevent loss of liquid. The parts are then 5 ready for operation and the piston may be removed to permit filling the barrel with the necessary liquid. Thereupon the piston is again inserted and the device is ready for use upon a patient.

10 While I have described the various features of my invention with reference to certain more or less particular embodiments, it is not restricted in its application to the details set forth, but may be used in various 15 ways without departing from the underlying features of the invention or the scope of the following claims.

I claim:

1. In a hypodermic syringe, the combination with a barrel having an opening which tapers toward its outer end, of a correspondingly tapered quickly removable needle carrier cooperating with said tapered opening in the barrel and held therein solely by frictional engagement, the taper of the barrel and carrier being such that the liquid pressure within the syringe tends to tighten the carrier in the barrel.

2. In a hypodermic syringe, the combination with a barrel having a tapered opening, of a needle carrier having a correspondingly

tapered portion adapted to fit in said opening and held there solely by frictional engagement, said tapered portion of the needle carrier being provided with a series of concentric grooves. 35

3. In a hypodermic syringe, the combination with a barrel having a tapered opening, of a needle carrier having a correspondingly tapered portion adapted to fit in said opening and held in the barrel solely by frictional engagement, the needle carrier having a reversely tapered portion at its inner end provided with sediment deflecting means. 40

4. In a hypodermic syringe, the combination with a barrel having an opening which tapers toward its outer end, of a correspondingly tapered, quickly removable needle carrier cooperating with said tapered opening in the barrel and held therein solely by frictional engagement, the needle carrier having an opening extending centrally, a needle arranged in said opening with its inner end fixedly attached at the inner end of the carrier, the taper of the barrel and carrier being such that liquid pressure within the syringe tends to tighten the carrier in the barrel. 55

In witness whereof, I have hereunto signed my name.

FREDERIC J. HOFSCHEIDER.
